TABLE

Angelo D'Ambrosio, New York, N. Y., Oscar Hiss,
Jersey City, N. J., and Fred Wildstein, New York, N. Y.

Application February 18, 1949, Serial No. 936

Term of patent 3½ years

(Cl. D33—14)

To all whom it may concern:

Be it known that we, Angelo D'Ambrosio, Oscar Hiss and Fred Wildstein, residing respectively in the county of the Bronx, city and State of New York; in the county of Hudson, Jersey City, and State of New Jersey; and in the county of Kings, city and State of New York, have invented a new, original, and ornamental Design for Table.

In the drawing:

Fig. 1 is a perspective view of a table showing our new design;

Fig. 2 is a top view;

Fig. 3 is a view taken through line 3—3 of Fig. 2, the broken vertical line being the vertical axis of the table; and

Fig. 4 is a sectional view taken through line 4—4 of Fig. 3.

We claim:

The ornamental design for a table, substantially as shown.

ANGELO D'AMBROSIO.
OSCAR HISS.
FRED WILDSTEIN.
